DESIGN FOR A DRESS OR SIMILAR ARTICLE

Abraham H. Morris, New York, N. Y.

Application July 14, 1938, Serial No. 78,470

Term of patent 3½ years

To all whom it may concern:

Be it known that Abraham H. Morris, a citizen of the United States and resident of New York city, in the county of New York, State of New York, has invented a new, original, and ornamental Design for a Dress or Similar Article, of which the following is a specification, reference being had to the accompanying drawing forming part thereof, and in which,

Fig. 1 is a front view of a dress, embodying my new design; and

Fig. 2 is a rear view of the same.

The characteristic feature of the design resides in the combination on the dress disclosed of the

three encircling bands, one at the waistline, one at the hipline, and one at the bustline, with bows at the front of each band, and a heart shaped neckline and backline, each having its apex extending to the topmost band, in association with high, narrow, short sleeves having bow trimmed bands, said neckline and backline being cut to expose substantially the entire shoulders of the wearer up to the sleeves, as shown.

I claim:—

The ornamental design for a dress or similar article, substantially as shown and described.

ABRAHAM H. MORRIS.
